UNITED STATES PATENT OFFICE

2,257,605

ADJUSTABLE FLAME HARDENING TORCH

Albert L. Hartley, Cincinnati, Ohio, assignor to
The R. K. Le Blond Machine Tool Company,
Cincinnati, Ohio, a corporation of Delaware

Application September 26, 1940, Serial No. 358,503

2 Claims. (Cl. 158—27.4)

This invention pertains to certain specific improvements in flame hardening torches with relation to controlling the flame jets from which issue the oxyacetylene flame for flame hardening the surfaces of work pieces. Particularly, this invention pertains to a novel construction of a flame hardening burner which is readily adapted by simple adjustment to controlling the number of flame jets which may be rendered operative for flame hardening purposes.

Another feature of this invention is to provide an adjustable control member in a flame hardening torch by which one or more or all of the flame jets of the flame hardening torch may be rendered operative by simple adjustment on the part of the operator.

A further object of this invention is to provide, in conjunction with such an adjustable torch arrangement, a dial indicating device which directly shows the number of flame jets which are in operation and which may be readily adjusted to effect the operation of the desired number of flame jets of the burner when flame hardening work pieces of various different widths and sizes so as to thereby effect the maximum efficiency of the burner as only the number of holes as definitely and specifically required for each particular work piece need be used.

Further features and advantages of this invention will appear from the detailed description of the drawings in which:

Figure I is an end view of the burner particularly showing the indicating dial for determining the number of flame jets which are in operation.

Figure II is a longitudinal section through the adjustable flame hardening torch shown on the line II—II of Figures I, III, and IV.

Figure III is a plan view of the adjustable flame hardening burner shown by the line III—III in Figures I and II.

Figure IV is a bottom view of the adjustable flame hardening torch, particularly showing the flame jets and coolant jets as indicated by the line IV—IV in Figures I and II.

Figure V is a diagrammatic view of the periphery of the tapered surface of the rotatable adjusting member of the flame hardening torch, particularly showing the arrangement of the various ports for effecting the progressive selection of each of the flame hardening jets when rotated to appropriate position.

This torch comprises a body 1, having the usual threaded projection 2 for attachment to

5 the mixing chamber of an oxyacetylene blow pipe. The combustible mixture of oxygen and acetylene is applied from the usual blow pipe through the central passageway 3 and then into the passageway 4 of the body portion 1 of the torch.

10 In the tapered bore 5 formed in the torch body 1 is nicely rotatably fitted the rotatable adjustable selecting member 6 having a mating peripheral tapered surface 7 nicely fitting against the bore 5 of the torch 1. Combustible mixture from the passageway 4 passes through the passageway 8 of the valve 1 to enter the annular slot 9 formed in the peripheral surface 1 of the selecting member 6. From this annular slot, the combustible mixture enters, through radial passageways 10 formed in the member 6, the chamber 11 which opens into the larger longitudinally extending chamber 12 formed in the member 6. This chamber 12 is connected through a series of predetermined spaced ports 13, which are formed in the control member 6. These ports extend radially outward from this chamber 12 through the peripheral surface 7 of the member 6, as shown diagrammatically in Figure V.

15 In order to provide proper distribution of the combustible fuel and to prevent the chamber 12 from igniting the combustible fuel at times when the burner is turned off or being initially lighted, a flash back checking device comprising the tubular member 14 having a central bore 15 connected to the chamber 11 in the adjusting member 6 and being connected through radially extending ports 16 which permit the fuel to pass into the chamber 12 but prevents flame from burning back from the ports 13 into the chamber 11 and the remaining passageways 8, 4, and 3 of the torch, which might result in damage due to the combustion and explosive burning of these mixtures in these passageways.

20 Suitable sealing means comprising the cap 17 held in proper place by the screws 18 serves to close off the small end of the tapered bore 5 of the valve to prevent entrance of dirt or foreign matter therein and also has a pilot projection 17a which helps support the flash back member 14.

25 In the torch body 1, are formed the flame jets 19 which are appropriately arranged in predetermined relation to the ports 13 in the adjusting member 6, so that as the adjusting member is rotated, various sets of jets 19 may be connected through the ports 13 with the chamber 12, so that any selection of flame jets may be had from 2

minimum, which in this instance is two when the particular ports 13a and 13b (Figure V) would be in alignment with the holes 19a and 19b of the flame jets 19, and so on until the adjusting member 6 were rotated so that all of the jets 19 would be suitably connected to the chamber 12 by appropriately rotating the member 6 to bring the maximum number of ports into alignment with these flame jets 19. In this way, the burner is arranged to most efficiently be easily and rapidly adapted to any width of work piece to be flame hardened without loss of gas where the work was narrower than that required of the full set of jets of the burner. Thus fuel economy is greatly improved and also the more efficient application of the flame to the specific type of work piece to be flame hardened is thereby accomplished.

The member 6 is provided with an integral threaded portion 20 upon which is threaded the nut 21 having abutment shoulders 21a and 21b respectively engaging the surface 1a of the torch body 1 and the surface 22a of the dial indicating collar 22 fixed on the surface 1a of the torch body 1 by appropriate screws 23a. Also on the projecting outer end of the adjusting member 6 is provided the squared end portion 6a, to which may be applied a suitable wrench for rotating the member 6 to the desired position. Also fixed to rotate with the member 6 is the indicating pointer 23 which travels over the dial indicating graduations 24 formed on the collar 22 in such a way that rotation of the member 6 to predetermined selected positions may be directly effected by noting the relative position of the pointer 23 with regard to the graduations 24. These graduations 24 are marked with numerals indicating the number of jets 19 brought into operative condition. The arrangement just described greatly facilitates the manipulation of the adjustment of the torch to bring the various desired numbers of flame jets 19 into operation.

In the event the plunger 6 should become tightly engaged or stuck in the bore 5, the nut 21 may be rotated by applying the usual spanner wrench in the spanner wrench holes 21c and rotated so as to cause its abutment surface 21a to bear against the surface 1a of the torch body 1 so as to dislodge its taper surface 1 from the bore 5 making it easy to turn to the desired selected position by rotating the member 6 by application of a wrench on the squared end portion 6a. After thus selecting the desired number of flame jets 19 to be put into operation by rotating the member 6 and noting the position of the pointer 23, the nut 21 is then rotated in opposite direction causing its abutment surface 21c to engage against the abutment surface 22a of the dial indicating collar 22 and again firmly lodge the member 6 in the bore 5 of the torch body 1

making a gas tight connection between the periphery 7 thereof and the tapered bore 5 in the burner 1.

Coolant medium for operation in conjunction with the flame hardening jets 19 is delivered through the annular slot 25 which is connected through the dual passageways 26 to the longitudinally extending coolant passageway 27 from which issue the coolant jets 28 for applying the coolant medium to the work immediately following the passage of the flame jets 19 over the work.

Thus in this combination of an adjustable flame hardening torch is provided a means whereby a torch may be provided with a plurality of flame jets and means whereby one or more or all of these jets may be quickly put into operation or cut out of operation by the simple manipulation of a control device associated with which is a dial indicating device for directly reading the condition desired of the burner.

Having thus fully set forth and described my invention what I claim as new and desire to secure by United States Letters Patent is:

1. In a gas burner, a body, a tapered bore in said body, flame orifices in said body opening into said bore, a rotatable tapered adjusting member mounted in said bore, means for rotating said adjusting member to selected positions, means for withdrawing said adjusting member from engagement with said bore when rotating said adjusting member and for firmly engaging said member with said bore when rotated to selected position, a fuel chamber in said adjustable member, ports in said member opening into said chamber and adapted to be brought into selective register with the various flame orifices by rotation of said member in said bore, and means in said body for connecting a source of fuel to said chamber.

2. In a gas burner, a body, a tapered bore in said body, flame orifices in said body opening into said bore, a rotatable tapered adjusting sleeve mounted in said bore, means for withdrawing or firmly engaging said sleeve in said bore comprising a nut threaded around a concentric stem portion at one end of said sleeve, means on said body engaging the faces of said nut adjacent its periphery to restrict its axial motion relative to said body, and means on said nut whereby it may be rotated in said body to axially adjust said sleeve longitudinally of said tapered bore in said body, a fuel chamber in said sleeve, radially extending ports in said sleeve opening into said chamber and adapted to be brought into selective register with the various flame orifices by rotation of said sleeve in said bore, and means in said body for connecting a source of fuel to said chamber.

ALBERT L. HARTLEY.
